UNITED STATES PATENT OFFICE

98,615

DESIGN FOR A BEDSTEAD

Marshall C. Pumphrey, Los Angeles, Calif., assignor to Barker Bros. Incorporated, Los Angeles, Calif.

Application November 12, 1935, Serial No. 59,507

Term of patent 3½ years

To all whom it may concern:

Be it known that I, Marshall C. Pumphrey, a citizen of the United States, residing at Los Angeles, county of Los Angeles, State of California, have invented a new, original, and ornamental Design for a Bedstead, of which the following is a specification, reference being had to the accompanying drawing, forming part thereof. The figure is a perspective view of a bedstead, showing my new design.

The side and back of the head-board and foot-board not shown are identical with the sides and ends illustrated in the drawing.

I claim:

The ornamental design for a bedstead as shown and described.

MARSHALL C. PUMPHREY.
